2 Claims

ABSTRACT OF THE DISCLOSURE

Improved adjustable sliding brush transformer having a coolant passageway between the brush track and brush supporting structure to reduce the transformer hot spot temperature. The brush supporting structure has a bifurcated portion. The bifurcated portion defines an outlet for the discharge of convective air currents in an axial direction away from the brush to reduce the hot spot temperature of the transformer. The brush supporting structure includes a guideway to maintain alignment of the brush relative to the brush track and to prevent binding of the brush in the brush supporting structure during operation.

This is a continuation of application Ser. No. 614,218 filed Feb. 6, 1967, now abandoned.

This invention relates to adjustable sliding brush transformers, and more particularly to improvements therein whereby the hot spot temperature of the transformer is substantially reduced.

Variable transformers of the sliding brush type typically have an autotransformer coil wound on a core with a surface portion of the coil forming a brush track. A brush consisting of one or more brush segments carried by a brush holder slides across and makes electrical contact with the brush track. The output current of the transformer is supplied from the winding through the brush to any desired external load. The output voltage of the transformer is varied by the selective positioning of the brush along the brush track.

In practice it often happens that the amount of current that can be supplied to a load and therefore the current rating of the transformer is limited by the maximum allowable temperature at the interface of the brush and brush track. The hot spot temperature, which is the highest temperature occurring at a point along the interface, is used in practice to determine the current rating of a transformer design.

When the hot spot temperature exceeds certain predetermined limits, the brush to brush track resistance increases heat generated at the interface. With continued operation under this condition the transformer may prematurely fail.

Another factor influencing hot spot temperature has been related to the alignment of the brush relative to the brush track. If the brush becomes misaligned, the interface area between the brush and brush track will be reduced and during operation the current density flowing through the contact face of the brush will correspondingly increase. With increased current density the hot spot temperature will also increase.

In view of the hot spot temperature problem, manufacturers of variable transformers have found it necessary in some applications to reduce the rated output current for a given unit. It will thus be appreciated that the maintenance of proper alignment and contact between the brush and track in a variable transformer and of the lowest possible hot spot temperature is extremely desirable.

2

Accordingly, it is a general object of the present invention to provide an improved adjustable sliding brush transformer characterized by relatively lower hot spot temperatures.

Another object of the present invention is to provide an improved sliding brush transformer wherein means are provided to promote and maintain proper alignment between a brush and brush track in the transformer.

Yet another object of the invention is to provide an improved sliding brush transformer wherein convection of air axially away from the brushes is achieved to reduce the hot spot temperature.

A still further object of the invention is to provide an improved adjustable brush transformer in which the above objects are obtained and which can be manufactured relatively easily and inexpensively.

In accordance with one form of the invention, I have provided an improved adjustable sliding brush transformer in which a brush supporting structure holds a brush against a brush track on the transformer winding. In the preferred embodiment of the invention, the brush supporting structure includes a brush arm having a bifurcated portion. The brush arm forms a cooling channel with a portion of the brush track and the bifurcations of the brush arm define an outlet for convective air currents communicating with the cooling channel. The outlet overlies portions of the brush and air can flow through the outlet axially away from the brush to reduce the hot spot temperature of the transformer. The brush arm in the preferred embodiment of the invention also includes means that guide the brush and maintain a desired orientation of the brush relative to the brush track.

The subject matter which I regard as my invention is set forth in the appended claims. The invention itself, however, together with further objects and advantages thereof may be best understood by referring to the following description taken in connection with the accompanying drawing in which:

FIGURE 1 is a perspective view of an adjustable sliding brush transformer embodying one form of the invention;

FIGURE 2 is an exploded view in perspective of a brush arm assembly used with the adjustable sliding brush transformer shown in FIGURE 1;

FIGURE 3 is a plan view of a portion of the transformer shown in FIGURE 1 and illustrates the relationship of the brush and outlet formed by a bifurcated brush arm; and

FIGURE 4 is a sectional view of a portion of the transformer of FIGURE 1.

Referring now to the drawing, my improved adjustable transformer, generally identified by numeral 18, comprises a core 19 of magnetic material substantially encased by an insulating material 23. Wound around the core of the transformer is a winding 20 of insulated wire. A portion of a surface of the winding has the insulation removed therefrom to form a brush track 21. The core and coil assembly of the transformer 18 may be bonded within the wall 27 on the base 21 with a resinous material 25 in the manner taught in United States patent application Ser. No. 582,024, filed Sept. 26, 1966 by Winston R. Judd and assigned to the assignee of the present application.

In the preferred embodiment, the brush holder assembly 28 is attached to the radial member and the brush holder 36 resiliently urges a plurality of brush segments 56 into electrical contact with the brush track 21. The radial member 24 has ventilation openings 26 therein as described in the above mentioned Judd application, and a control knob 30 is provided for manually setting the location of the brush on brush track 21.

When the transformer is used to supply current to a load, the output current flows from the winding 20 through the brush segments 56, the brush supporting plate 62, the brush holder 36, and a conducting ring 29 as disclosed and claimed in U.S. Patent No. 3,160,841 owned by the assignee of the present application. A brush mounted in housing 16 bears against the conducting ring 29 and is connected to the output terminal 13 on the terminal plate 10. It will be appreciated that the provision of terminals 11, 12, 14 and 15 on the terminal plate 10 in the manner shown provides flexibility in selecting the desired range of voltage for application to the load.

The brush carrying structure includes the radial member 24, brush holder 36, and brush assembly 54. As shown in FIGURE 2, each brush segment 56 is biased away from the backing plate 62 by a spring 58. The brush conductors 60, having one end embedded in a brush segment 56 and another end thereof secured to the backing plate 62 by suitable means such as a spot weld, hold the springs 58 in a slightly compressed condition. Holes 63 in the backing plate 62 are aligned with the holes 33 in the brush arm 36 and screws hold the plate and arm in assembled relation. After assembly, the brush segments 56 are slidably disposed within the guide way 39 of the brush holder 36.

The bifurcated brush holder 36 includes two bifurcations 40, 42 and two leg portions 34 which form opposite sides of a brush receiving guide way 39. Preferably sufficient clearance between the brush and brush guide way 39 is provided so that the brush may be continually biased against the brush track 21 during operation. However, the clearance should be kept as small as possible so that the brush does not vibrate during operation and cause arcing between the brush and brush track. In order to maintain proper alignment of the brush segments 56 relative to the brush track 21 and prevent binding of the brush in the guide way 39 due to thermal expansion and thermally induced warping of the leg portions 34, the bridging section 38 is provided between leg portions 34 of the brush arm 36. It will thus be appreciated that the bridging section 38 provides dimensional stability for the guide way 39 during operation.

Now having reference to FIGURES 3 and 4, it will be seen that the brush holder 36 is held in spaced relation to the brush track 21 during operation to form a cooling channel between the brush holder 36 and brush track 21. As can be seen in FIGURE 3, portions of the brush segments 56 are positioned in the cooling channel and lie directly below a coolant outlet defined by bifurcations 40, 42, the surface 37 of brush holder 36 and the conducting ring 29. As shown in FIGURE 4, a cooling medium such as forced or convective air currents will flow in the direction of the arrow axially along and axially away from the brush segments 56 through the outlet. It will also be seen from FIGURE 4 that coolant can escape radially outwardly from the transformer across surface 37 of the brush holder 36.

In the actual reduction to practice of the invention the brush holder 36 was die cast zinc. The bifurcated portions 40, 42 of the brush holder 36 had recessed surfaces 46, 48 so that the heads of mounting screws used to attach the brush holder to the radial member 24 did not project beyond the brush arm 36. The tolerance between the guide way 39 and the brush segments 56 was less, from about .0005 inch to about .003 inch, which was sufficient to permit the springs 58 to bias the brush segments 56 into good electrical contact with the brush track 21 during operation but was also sufficiently small to prevent cocking of the brush segments 56 within the guide way 39 which could cause misalignment of the brush with respect to the brush track.

Tests were run on a variable transformer with and without an improved convective air flow outlet brush holder arrangement to obtain comparative data relating to hot spot temperatures. In order to reduce the variables in the

test, the same core and coil unit as well as the same load was used in each test. To further reduce variables in the tests the same brush holder and brush, similar to the exemplified brush holder and brush, were used in each test. However, during the first test the improved convective air flow outlet brush holder was temporarily modified by closing the outlet with putty in order to approximately simulate a transformer arrangement without an air flow outlet.

At the beginning of the second test run the putty was removed, with care being taken not to disturb the brush setting, so that the second set of test data would indicate the range of hot spot temperatures present in a transformer having the improved convective air flow outlet brush holder arrangement.

During both tests, temperature indicating paint, stated to have a temperature indicating accuracy of one per cent, and manufactured by the Tempil Manufacturing Company of New York was used to obtain an indication of hot spot temperatures. As is understood by persons skilled in the art, different formulations of the Tempil paint is manufactured and individual formulations exhibit pigmentation changes when heated above the predetermined temperature for each particular formulation.

In both test, 236 volts were applied across terminals 11 and 14 and 30 amperes of current at 120 volts were supplied to the load from terminals 11 and 13. The output voltage of 120 volts corresponded to an approximately centered position of the brush on the brush track.

After the transformer had been operated continuously for over twenty hours in each test, successive formulations of the Tempil paint were applied to the brush track adjacent the brush and observed for pigmentation changes. The temperature sensitivity of each successive Tempil paint formulation differed from the preceding formulation by three to four degrees centigrade, and it was therefore possible to bracket within a few degrees a temperature which was indicative of the hot spot temperature during each test.

The results of the first test showed that in the transformer without an improved convective air flow outlet brush holder the hot spot temperature was between 173 and 177 degrees centigrade. However, the second test showed that in the exemplified transformer with an improved convective air flow outlet brush holder the hot spot temperature was between 142 and 146 degrees centigrade. It will thus be appreciated that nearly an 18 percent reduction in hot spot temperature was observed in the transformer embodying the convective air flow outlet aspect of the present invention.

It will also be appreciated that by reducing the hot spot temperature in variable transformers, the output current rating for a given frame size and core and coil size can be increased.

From the foregoing description it will now be appreciated that I have provided an improved variable transformer of the adjustable brush type which is particularly characterized by reduced hot spot temperatures in the transformer. It will also be appreciated that I have provided a solution for the problem of brushes binding in brush holders as well as an improved arrangement wherein in the alignment between a brush and brush track can be maintained in practice.

While I have illustrated and described a particular exemplification of my invention, it will be apparent that many modifications may be made as will be apparent to those skilled in the art. It is to be understood therefore that this invention is not intended to be limited to the particular embodiment shown and that it is intended by the appended claims to cover all modifications that come within the spirit and scope of this invention.

I claim:

1. In an adjustable sliding brush transformer comprising an annular core and coil assembly having a substantially vertically extending central axis and a brush

track therearound, a brush resiliently engaging the brush track and making sliding electrical contact therewith, the improvement in said transformer comprising: brush carrying structure having means for guiding the brush to maintain a predetermined orientation of said brush relative to said brush track, and support means supporting said brush carrying structure in spaced relation to the brush track to form a cooling channel between said brush carrying structure and brush track, said brush carrying structure comprising a bifurcated portion for attachment to said support means, and said bifurcated portion having a pair of bifurcations extending substantially radially inwardly toward said central axis and said pair of bifurcations defining an outlet communicating with said channel and overlying portions of the brush engaging said brush track whereby convective air currents move past the brush track and brush and discharge in an axial direction away from said brush through said outlet to thereby reduce the hot spot temperature of the brush.

2. A sliding brush transformer comprising an annular core and coil assembly having a substantially vertically extending central axis and a brush track surface, a brush for making uniform sliding electrical contact with said brush track surface, brush supporting structure for carrying said brush and maintaining a predetermined orientation of said brush relative to said brush track, means for mounting said brush supporting structure in spaced relation to the brush track to form a cooling passageway there-

5 between, said means for mounting said brush supporting structure including a bifurcated portion, said bifurcated portion having a pair of bifurcations extending substantially radially inwardly toward said central axis and said pair of bifurcations defining therebetween an outlet for convective air currents communicating with said cooling passageway and overlying portions of said brush whereby convective air currents flowing axially along the brush discharge through the outlet in an axial direction away from the brush thereby to reduce the hot spot temperature of the transformer, means to prevent binding of the brush in the brush supporting structure during operation, and means cooperating with said brush supporting structure and said brush for resiliently urging said brush into electrical contact with the track.
